MASSAGING ROLLER

John Waldeck, 2764 Faber Ave., Cincinnati, Ohio 45211

Filed Dec. 8, 1965, Ser. No. 118

Term of patent 14 years

(Cl. D83—1)

Fig. 1

Fig. 2

Fig. 3

FIGURE 1 is a side elevation of a massaging roller embodying my new design.

FIGURE 2 is an end elevation thereof.

FIGURE 3 is a plan view thereof.

The side and end of the massaging roller not shown are the same as the side and end shown.

I claim:

The ornamental design for a massaging roller, substantially as shown and described.
